UNITED STATES PATENT OFFICE

GEORGE L. REICHHHELM, OF ELIZABETH, NEW JERSEY, ASSIGNOR TO THE GASIFIER COMPANY, OF ELIZABETH, NEW JERSEY, A CORPORATION OF NEW JERSEY

OIL GASIFIER

Original application filed August 15, 1921, Serial No. 492,237. Divided and this application filed November 24, 1924. Serial No. 752,049.

The present invention relates to gasifiers.

The present application is a division of application for United States Letters Patent, Serial No. 492,237, filed by the present applicant on August 15, 1921.

The present invention relates to mechanism for converting low-grade liquid fuels, such as heavy fuel oil, into a light, highly combustible gas. Various devices have been 10 designed for gasifying low-grade fuel oil, some of which operate upon the principle of causing the oil to be separated, vaporized or broken up into globules, supplied with air and projected against a hot surface. The 15 globules referred to are thereby supplied with sufficient heat to still more finely divide them resulting in a more or less combustible mixture. Devices of this sort have been open 20 to objections for the reason that they are wasteful of oil, require a large space, entail a large loss of energy and cause deposits of carbon.

An object of the present invention is to provide a gasifier in which the characteristics of 25 the gas may be readily controlled.

A further object is to provide mechanism which will convert liquid fuel into a fixed gas, whereby said gas may be distributed through 30 pipes, tubes or manifolds without condensation.

A further object is to provide a gasifier for converting low-grade liquid fuel into proper form for use in internal combustion engines or gas turbines.

A further object is to provide mechanism for converting low grade liquid fuel into a gas which will mix very readily with air and therefore permit combustion in a minimum 35 of space.

A further object is to provide a gasifier for low grade liquid fuels which will occupy a minimum of space.

A further object is to provide a gasifier for fractionally distilling an oil fuel in which the degree to which the fuel may be divided 45 may be readily controlled.

A further object is to provide a gasifier in which carbon deposits will be very greatly minimized or substantially eliminated.

Referring to the drawings—

Figure 1 is an elevational view showing one embodiment of the present invention;

Figure 2 is a sectional elevation taken along the line 2—2 of Figure 1, showing certain details of the regulating mechanism according to the present invention; 55

Figure 3 is a vertical sectional view illustrating the combustion chamber and parts adjacent thereto;

Figure 4 is a sectional view taken along the 60 line 4—4 of Figure 3;

Figure 5 is a view in elevation of part of the apparatus; and

Figure 6 is a sectional view taken along the 65 line 6—6 of Figure 3.

In order to provide a perspective of the invention, it may be stated briefly that oil or other liquid fuel is subjected to air and with the air projected in an atomized state into a combustion chamber. Said fuel is preferably 70

caused to take a curved or swirling motion by means of jets of oxygen-containing fluid, preferably air. The fuel is thereby prevented from impinging directly upon the wall of the chamber and, at the same time a reg- 75

ulatable supply of air is provided. During this swirling movement, there is a very thorough mixture of air with the superficial portion of the stream of vaporized oil and air and there is combustion at a high tem- 80

perature which vaporizes the oil and maintains the ejecting nozzle at a high temperature. According to the structure illustrated, the intimate mixture of air and oil vapor is directed into a superheating chamber where 85

further combustion raises the mixture to an extremely high temperature, completely gasifying the fuel and fixing said gas, whereby same will not condense when subsequently passed into a cooler container. Briefly stated 90 the oil is successively atomized, vaporized and gasified.

Referring first to Figures 1, 3 and 6, the numeral 10 indicates a drum having a pair of side walls 11 and 12 and a circular band 13. 95 Mounted within said drum is a housing 14 of novel conformation, which housing is illustrated as being integral with the side wall 11. It is within this housing 14 that the fuel is gasified and fixed in gaseous condition. 100

Said housing 14 comprises a combustion chamber 15, a secondary or superheating chamber 16 and a portion 17 provided with a baffle wall 18 to provide a tortuous passage, 5 the functions of which will be described hereinafter.

Mounted in the drum 10 in a position to discharge into the chamber 15 is a nozzle 19, which may have screw-threaded engagement with the housing 14. Said nozzle forms part of the mechanism for breaking up liquid oil into a spray or vapor and mixing air therewith. Said vaporizing mechanism, which is best illustrated in 15 Figure 2, is indicated as a whole by the numeral 20. As illustrated, said mechanism comprises a pair of arms 21 and 22, which may be secured together in parallel relation. Of these arms, the one indicated by the numeral 20 21 is designed to admit oil and for this purpose is provided at the bottom thereof with an inlet 23. The inflow of oil is controlled by means of a needle valve 24 which is mounted on the screw-threaded stem 25 and which 25 is manually controlled by means of the hand wheel 26.

The arm 22 serves as means for admitting air and is provided with an inlet port 27 which communicates with a chamber 28, extending longitudinally of the arm 22. Mounted for reciprocating movement within the arm 22 is a tube 29, which is adapted to carry oil. Communicating with the needle valve 24 of the arm 21 is the pipe connection 30 which 35 provides communication for oil from the inlet port 23 through the tube 31 to the tube 29. It will be understood, of course, that the two sections 31 of tubing will be connected together.

40 Air which is admitted to the port 27 may pass downwardly through nozzle 19 into the combustion chamber 15 and has another means of exit through the pipe 32, which communicates with the longitudinal chamber 28 at a point which may conveniently be above the inlet port 27. Said pipe 32 communicates with the side of the drum 10 and provides a supply of air for the purpose which will be described hereinafter. The tube 29 has adjustably mounted thereon the sliding member 33, which forms a close fit within the chamber in the arm 22. Said sliding member 33 forms a closure for the opening of pipe 32 and controls the supply of air through 45 said pipe 32. The tube 29 is provided with a contracted end portion or nozzle 34, which is adapted to cooperate with the wall of nozzle 19 to vary the area of the outlet port for the air flowing downwardly through chamber 28. Movement of the tube 29 will therefore 50 govern the flow of air through both the nozzle 19 and the pipe 32. The tube 29 is provided with a collar 35, which cooperates with a nut 36 within the arm 22. Said nut 36 has a longitudinally extending shank 37, which

forms the support for a gear 38. Rotation of said gear 38 operates through nut 36 and collar 35 to effect vertical movement of the tube 29. The stem 25, which controls the flow of oil is provided with a gear 39, said 70 gears 38 and 39 being connected together through an idler pinion 40, which pinion 40 is resiliently held in position to engage the two gears 38 and 39 by the spring 41. Independent adjustment of stem 25 and tube 29 75 may be accomplished by raising the pinion 40 against the tension of spring 41, thereby permitting the rotation of gear 38 or gear 39 independently of the other. When the correct ratio between the supply of oil and the supply of air has been determined and the stem 25 and tube 29 have been properly set, the gears 38 and 39 will be connected together by means of pinion 40 and this ratio 80 of oil to air will be maintained regardless of changes in the total amount of oil and air being supplied to the gasifier. Relative adjustments of stem 25 and tube 29 may be necessary when changes are made in the 85 fuel oil supplied to the gasifier.

90 It will be noted that portions of the inner wall of the chamber 15 are curved about axes substantially normal to the axis of the nozzle 19.

Air, which will be referred to as secondary air, which passes from the chamber 28 through pipe 32 to the drum 10, will be admitted to the combustion chamber through the orifices 42 and orifices 43, which orifices lie in chords intersecting the curved inner 100 wall of said chamber. Only a few orifices are illustrated in Figure 3, but it will be understood that other orifices will be provided in a number of planes. Said orifices 42 and 43 will preferably have a direction 105 whereby jets emitted from said orifices into the combustion chamber 15 will set up a tangential or swirling movement to fluid within said combustion chamber 15. For this purpose orifices 42 are so disposed as to direct 110 air against the superficial particles of the main stream of oil and air in a direction opposed to the direction of flow of said particles. The pressure of the air through said orifices 42, as referred to above, sets up a 115 swirling movement, producing a very thorough mixture of air with the superficial portion of the stream of vaporized oil and air, and there is combustion at a high temperature which vaporizes the oil and maintains the ejecting nozzle at a high temperature. It will be noted in Figure 3 that the neck between chamber 15 and superheating chamber 16 is not symmetrical with chamber 15, but is so formed that it directs fluid from chamber 15 downwardly into said superheating chamber 16. As illustrated, flames emitted inwardly from orifices 42, will set up a swirling movement in the chamber 15 in a 120 counterclockwise direction. This swirling 125 130

movement will be aided by jets emitted inwardly from orifices 42 and jets emitted inwardly by orifices 43, the latter mentioned jets also tending to force the gases down into the superheating chamber 16. The walls of superheating chamber 16 are curved to cause the gases to be diverted down toward the baffle plate 18. The gases do not come in contact with any sharp corners and in passing around said baffle plate are still further mixed. Located below the baffle plate 18 is the outlet 44, through which the oil gases may be led off to burners, reservoirs or other devices.

In starting the above described mechanism for gasifying functions, the spray of oil mixed with air may be ignited in any preferred way. In Figures 1 and 3, a spark plug 45 is provided for this purpose. Instead of a spark plug an ordinary taper may be used. Figure 4 illustrates a structure having a hole 46 which may receive a spark plug, a taper or any other igniting means. Said hole 46 is provided with a closure member 47 which may be removably held in place by means of the yoke 48 and the screw-threaded member 49.

The numeral 50 indicates a sight tube communicating with the chamber 15. Said sight tube 50 is provided with a mica window 51 through which the combustion within chamber 15 (Figure 3) may be observed. Said window 51 may be provided with a cover 52, which may be removably held in place by means of the yoke 53 and screw-threaded member 54.

Briefly reviewing the mode of operation of the above described embodiment of the present invention, it may be stated that liquid fuel is admitted through the port 23, and air is admitted through the port 27 (Figure 2). The correct ratio between the flow of liquid fuel and air may be adjusted by throwing the pinon 40 out of mesh with gears 38 and 39 and moving said gears independently of one another until the correct ratio is obtained. Said pinon 40 may then be permitted to snap back into mesh with the gears 38 and 39, whereby to provide unitary control for both liquid fuel and air. Liquid fuel will pass from port 23 past needle valve 24 into tube 31, thence through tube 29 to the nozzle 19. Air from the port 27 will also issue from nozzle 19 and will cause liquid fuel to assume the form of an atomized stream projected from said nozzle 19 into the chamber 15 (Figure 3). Not only will air pass to the nozzle 19, but will also pass through the pipe 32, which is controlled by the sliding member 33. The pipe 32 will lead air to the drum 10, where said air will be admitted to the chamber 15 through orifices 42 and orifices 43. The jets issuing from these orifices will act as fluid baffles uniting with the superficial particles of the spray projected from

the nozzle 19, whereby there will be no impinging of said spray directly upon any solid wall. The air in said jets unites with the superficial portion of the stream to form a combustible mixture within the chamber 15 and secondary chamber 16 which is ignited by means of the spark plug 45, or other preferred means, and combustion at a high temperature will occur. Only a limited supply of air will be admitted, sufficient for combining with the superficial part of the stream of atomized fuel. The heat generated by the combustion of the air and said part of the fuel will gasify the remainder of said fuel and fix said gas. Moreover, the combustion of said swirling mixture will maintain the co-operating nozzles 19 and 34 at a high temperature. Due to the contour of the housing 14 and the action of the jets issuing from orifices 42 and orifices 43, the mixture of air and liquid fuel will be caused to take a circuitous or swirling motion resulting in the complete commingling of the superficial particles of oil with air or complete commingling of air with a part of the main stream. Combustion will be with a blue flame, leaving no deposit of carbon.

The fact that a blue flame, indicating perfect combustion, is maintained in the presence of a superabundance of gas, should be particularly noted. A reasonable explanation for this phenomenon seems to be that as soon as the gasifier is heated, the product issuing from nozzle 19 is projected throughout the entire combustion chamber and the air jets, issuing at low velocity relatively to the velocity of the stream issuing from the nozzle 19, from apertures 42 and 43 combine at once with the superficial portions of said product resulting in a blue flame.

The air admitted through the apertures 42 and 43, unites with the superficial portion of the stream of atomized oil and air to form a combustible mixture around the core of the stream, the core of the stream being non-combustible because of insufficient air. The core of the stream projected from the nozzle 19 is therefore surrounded by an envelope of flame whereby it is vaporized and gasified. The velocity of flow of the stream may be greater than the rate of flame propagation, but due to the fact that the air supply through the holes 42, 42, and 43, 43, is at a lower rate of flow than the rate of flame propagation, combustion is maintained in the space surrounding the stream which ignites the outer layer of the stream even when the velocity of the stream is greater than the rate of flame propagation.

There is no deposit of carbon or soot due to the fact that if some of the carbon and hydrogen bonds should break down, the products of combustion will form a mixture with the released carbon, so that the products of combustion serve as a conveyor for the re-

leased carbon, thus keeping it in a suspended state.

The apparatus is very compact and is therefore well adapted for motor cars, locomotives and other devices wherein space is limited. The apparatus is readily adaptable for other purposes than that described in detail above. For instance, the apparatus may be used for the distillation of heavy liquid fuel into lighter and more combustible liquids, different condensation chambers being provided for this purpose.

One apparatus for practicing the present invention has been described in detail. Many modifications will occur to those skilled in the art. It is intended in this application to cover all modifications of my improved process that fall within the scope of the invention as defined by the appended claims.

20 I claim:

1. An oil gasifier comprising a gasifying chamber, an inlet valve for liquid fuel, a nozzle leading to said chamber, means providing a passage from said valve to said nozzle, said 25 nozzle having an air inlet and being adapted to project a spray of oil mixed with air into said chamber, control means for said valve, control means for said nozzle, gearing including an idler gear connecting said control 30 means, said idler gear being readily thrown into or out of gear, whereby said control means may be adjusted relative to one another or may be controlled as a unit.

2. An oil gasifier comprising a nozzle for 35 projecting a mixture of liquid fuel vapor and air, a primary qualifying chamber for receiving fluid from said nozzle, said primary chamber having its inner wall curved about axes normal to the axis of said nozzle to deflect said vapor and air back toward said nozzle, said primary chamber having air delivery means in the walls thereof for admitting air into said primary chamber in directions to set up a swirl within said primary 45 chamber about an axis normal to the axis of said nozzle, and a secondary gasifying chamber communicating with said primary chamber, communication between said chambers being through a neck unsymmetrically disposed, relative to said two chambers.

3. An oil gasifier comprising a nozzle for 55 projecting a mixture of liquid fuel vapor and air, a primary gasifying chamber for receiving fluid from said nozzle, said primary chamber having its inner wall curved about axes normal to the axis of said nozzle to deflect said fluid back toward said nozzle with a swirling motion, and a secondary gasifying chamber communicating with said primary chamber through a neck, said neck being inclined relative to the axis of said nozzle, whereby the outer region of the swirling mixture within said primary chamber is deflected into said secondary chamber.

65 4. An oil gasifier comprising a nozzle for

projecting a mixture of liquid fuel vapor and air, a primary gasifying chamber for receiving fluid from said nozzle, said primary chamber having its inner wall curved about axes normal to the axis of said nozzle to deflect said fluid back toward said nozzle with a swirling motion and having air jets for aiding said swirling motion about an axis normal to the axis of said nozzle, and a secondary gasifying chamber communicating with said primary chamber through a neck unsymmetrically disposed relative to said chambers, said neck having its axis inclined toward the oncoming particles being swirled about in said primary chamber.

5. An oil gasifier including a nozzle for projecting a mixture of liquid fuel vapor and air, a primary gasifying chamber for receiving said mixture from said nozzle, said primary chamber having portions of its inner wall curved about axes normal to the axis of said nozzle, and a secondary gasifying chamber communicating with said primary chamber through a neck unsymmetrically disposed relative to said axis of said nozzle.

6. An oil gasifier including a nozzle for projecting a mixture of liquid fuel vapor and air, a primary gasifying chamber for receiving said mixture from said nozzle, said primary chamber having portions of its inner wall curved about axes normal to the axis of said nozzle, and a secondary gasifying chamber communicating with said primary chamber through a neck unsymmetrically disposed relative to said axis of said nozzle, a portion of the wall of said secondary chamber being globular in form, whereby to promote swirling within said secondary chamber.

7. An oil gasifier comprising a nozzle for projecting a mixture of liquid fuel vapor and air, a primary gasifying chamber for receiving said mixture from said nozzle, said chamber having its inner wall curved about axes normal to said nozzle for deflecting said mixture back toward said nozzle without abrupt turns, said primary chamber having air delivery means in the walls thereof for admitting air into said primary chamber in directions to set up a swirl within said primary chamber about an axis normal to the axis of said nozzle, a secondary gasifying chamber communicating with said primary chamber, communication between said chambers being through a neck unsymmetrically disposed relative to said two chambers, an air container enclosing said chambers, said primary chamber having communication with said air container through said air delivery means.

8. An oil gasifier comprising a nozzle for projecting a mixture of liquid fuel vapor and air, a primary gasifying chamber for receiving said mixture from said nozzle, said chamber having its inner wall curved about axes normal to said nozzle for deflecting said mixture back toward said nozzle without abrupt

- turns, said primary chamber being shaped to promote a swirling motion of said mixture within said primary chamber, and a secondary gasifying chamber communicating with said primary chamber through a neck unsymmetrically disposed relative to said chambers, said neck having its axis inclined toward the oncoming particles being swirled about in said primary chamber.
- 5 9. A gasifier for converting a heavy liquid fuel into a combustible gas, comprising means for delivering a stream of said fuel in atomized form, a gasifying chamber for receiving said stream, said chamber having portions of its inner wall curved about axes normal to the axis of said nozzle, said chamber being provided with passageways for admitting a secondary supply of air in a direction relative to said curved wall portions 15 midway between the corresponding tangent and the corresponding normal line to cause a circumferential movement within said chamber.
- 10 10. Apparatus for converting a liquid fuel into a combustible gas, which comprises means for projecting a stream of primary air and oil particles, a gasifying chamber for receiving said stream, said chamber having inner wall portions curved about axes 20 normal to the axis of said projecting means, said chamber having passageways arranged relative to said curved wall portions in lines midway between the corresponding tangents and the corresponding normal lines of said 25 curved wall portions for commingling a part of said stream with secondary air jets to form a superficial combustible mixture, whereby said combustible mixture when ignited may convert the unconsumed air particles into gas of predetermined fixation.
- 30 11. In an oil gasifier, in combination, a gasifying chamber, a nozzle for projecting a mixture of oil and air into said chamber, the inner wall of said chamber being curved 35 about axes normal to the axis of said nozzle and one side of said inner wall being longer than the other side thereof, said chamber having an outlet defining the extremities of 40 said sides unsymmetrically disposed relative to the axis of projection of said nozzle whereby to deflect superficial particles of said mixture projected by said nozzle back into proximity with said nozzle, and air supply means, said chamber being provided with passageways 45 providing communication between said air supply means and the interior of said chamber, said passageways being disposed in positions to direct air in directions to set up a circumferential swirl within said chamber.
- 50 12. In an oil gasifier, in combination, a gasifying chamber, a nozzle for projecting a mixture of oil and air into said chamber, the inner wall of said chamber being curved 55 about axes normal to the axis of said nozzle and one side of said inner wall being longer than the other side thereof, said chamber having an outlet defining the extremities of said sides unsymmetrically disposed relative to the axis of projection of said nozzle whereby to deflect superficial particles of said mixture projected by said nozzle back into proximity with said nozzle, and air supply means, said chamber being provided with passageways 60 providing communication between said air supply means and the interior of said chamber, said passageways being disposed in positions to direct air in directions to set up a circumferential swirl within said chamber.
- 65 13. In an oil gasifier, in combination, a gasifying chamber having curved inner wall portions, means for projecting a mixture of air and atomized liquid fuel into said chamber, said curved inner wall portions being curved about axes normal to the axis of said projecting means, one side of said chamber being longer than the other side thereof, said chamber having an outlet unsymmetrically disposed relative to said projecting means, said outlet defining the extremities of said sides, said chamber providing passageways, means for projecting air through said passageways into the superficial portion of said mixture whereby to form a superficial combustible envelope, said passageways being disposed in a direction to communicate a circumferential movement to said mixture about axes normal to the axis of said projecting means.
- 70 14. In an oil gasifier, in combination, a receptacle, a gasifying chamber disposed within said receptacle, means for delivering a mixture of air and atomized liquid fuel into said chamber, means for delivering air into said receptacle, unitary control means for said two delivering means, said chamber being provided with passageways communicating with the interior of said receptacle which passageways are disposed in positions to direct air from said receptacle in directions to set up a circumferential movement in the mixture in said chamber about axes normal to the axis of said delivering means, one wall of said chamber being longer than the opposite wall thereof, said chamber having an outlet unsymmetrically disposed relative to said delivering means, said outlet defining the extremities of said sides.
- 75 15. An oil gasifier including a nozzle for projecting a mixture of liquid fuel vapor and air, a gasifying chamber for receiving fluid from said nozzle and having its inner wall curved about axes normal to the axis of said nozzle to deflect the outer particles of said mixture back toward said nozzle, said chamber having passages through the walls thereof for admitting air into said chamber, said passages having their axes so disposed
- 80 85 90 95 100 105 110 115 120 125 130

as to set up a whirl in said mixture about an axis normal to the axis of said nozzle, one side wall of said chamber being longer than the opposite side wall thereof, said chamber having an outlet unsymmetrically disposed relative to the axis of projection of said nozzle.

16. An oil gasifier comprising a housing providing a gasifying chamber, an air container surrounding said housing, a nozzle communicating with said chamber for delivering a mixture of oil spray and air into said chamber, one side of said chamber being longer than the opposite side thereof, said chamber having an outlet unsymmetrically disposed relative to the axis of projection of said nozzle, the inner wall of said chamber being curved to deflect particles of oil spray and air back toward said nozzle, and an air container surrounding said housing, said housing being provided with passages connecting the interior thereof with said air container, said passages having their axes so disposed as to set up a swirl within said chamber about an axis normal to the axis of said nozzle.

17. An oil gasifier comprising, in combination, a nozzle, a gasifying chamber having inner wall portions curved about axes normal to the axis of said nozzle, said chamber being provided with means for setting up a fluid baffle for said mixture in a direction to set up a swirl within said chamber about an axis normal to the axis of said nozzle, one side wall of said chamber being longer than the opposite side wall thereof, said chamber having an outlet defining the extremities of said side walls unsymmetrically disposed relative to the axis of projection of said nozzle.

40 Signed at Elizabeth, New Jersey, this 15th day of November, 1924.

GEORGE L. REICHEL M.
